UNITED STATES PATENT OFFICE

92,396

DESIGN FOR A VENDING MACHINE

Myer Gensburg, Chicago, Ill.

Application April 6, 1934, Serial No. 51,333

Term of patent 3½ years

To all whom it may concern:

Be it known that I, MYER GENSBURG, a citizen of the United States, residing at Chicago, in the county of Cook and State of Illinois, have invented a new, original, and ornamental Design for a Vending Machine, of which the following is a specification, reference being had to the accompanying drawing forming a part thereof, and in which:

The single figure is a perspective view showing the new design.

I claim:

The ornamental design for a vending machine as shown.

MYER GENSBURG.
